DESIGN FOR A BLOUSE

Irving Geist, New York, N. Y.

Application August 16, 1941, Serial No. 102,868

Term of patent 3½ years

To all whom it may concern:

Be it known that I, Irving Geist, a citizen of the United States, residing in New York city, in the county of New York and State of New York, have invented a new, original, and ornamental Design for a Blouse, of which the following is a specification, reference being had to the accompanying drawing, forming part thereof.

Fig. 1 is a front view of a blouse showing my new design.

Fig. 2 is a rear view of Fig. 1, and

Fig. 3 is a fragmentary view thereof.

The characteristic feature of my design resides in the combination on the specific blouse disclosed of the specific multi-rows of parallel finished stitch trim appearing around the sleeves, collar and the inner and outer sides of the paneled front opening, as shown.

I claim:

The ornamental design for a blouse, substantially as shown and described.

IRVING GEIST.
